(57) **CLAIM**

The ornamental design for a tyre, as shown and described.

DESCRIPTION

FIG. 1 is the front view of a tyre showing my new design;

FIG. 2 is the rear view thereof;

FIG. 3 is the left view thereof;

FIG. 4 is the right view thereof;

FIG. 5 is the top view thereof;

FIG. 6 is the bottom view thereof; and,

FIG. 7 is the perspective view thereof.

The broken lines shown in FIGS. 3, 4 and 7 illustrate portions
of the tyre that form no part of the claimed design.
